UNITED STATES PATENT OFFICE.

ANDREW NICHOLS, OF BOSTON, MASSACHUSETTS, ASSIGNOR TO HIMSELF
AND CHARLES GRANT, JR., OF SAME PLACE.

SHOE.

SPECIFICATION forming part of Letters Patent No. 230,649, dated August 3, 1880.

Application filed June 28, 1880. (No model.)

To all whom it may concern:

Be it known that I, ANDREW NICHOLS, of Boston, of the county of Suffolk and State of Massachusetts, have invented a new and useful Improvement in Shoes; and I do hereby declare the same to be described in the following specification, and represented in the accompanying drawings, of which—

Figure 1 is a longitudinal section of a shoe embracing my invention. Fig. 2 is a transverse section taken through the heel. Fig. 3 is a longitudinal section, and Fig. 4 a transverse section, of the heel-crowning re-enforce, to be described. Fig. 5 is a side view of the shoe having its sole split at the heel for reception of the said re-enforce.

My improvement relates to what is known in trade and by shoe-makers as a "turned" shoe—that is, a child's shoe having its upper turned inside out, and when in such condition lasted and sewed to the inner surface of a sole, the whole being subsequently turned inside out. The stitches of the sewing do not go through the sole from its inner to its outer surface, but simply pass through the lap of the upper and go a short distance into and then out of the next adjacent part of the sole.

In making a shoe of this kind it, before the date of my invention, has been considered difficult, if not impossible, to form the sole with what manufacturers term a "spring-heel"—that is a heel convex on its outer surface and in one piece with the rest of the sole, my invention being to effect this purpose.

After the upper and the sole have been sewed together and the shoe turned so as to bring outward the outside surfaces of the upper and sole, I slit the sole through the heel portion thereof to the shank, and midway, or about

midway, between the outer surface of the sole and the stitches connecting the sole to the upper, the slit being parallel, or about so, to the said surface; and having turned or folded back toward or upon the shank the free part of the heel of the sole, I place on the part from which said free part was separated a crowned re-enforce or convex piece of sole-leather or other suitable material, and nail, peg, or otherwise secure it in place. Having done this I turn the said free part over upon the said re-enforce, and cement or otherwise properly fasten it thereto, thereby causing the said free part, on its outer surface, to be convex and the heel to present the appearance of a spring-heel.

In the drawings, A denotes the shoe-upper; B, the sole; C, the re-enforce; a, the stitching of the sole and upper, and b the cut or slit made in the heel of the sole, the free part produced by such cut being shown at c.

I claim as my invention as follows, viz: 60

1. As an improved manufacture, a turned shoe having its sole split or slit in its heel, as described; and a crowning re-enforce, as explained, arranged in the slit and fixed to the sole, substantially as set forth. 65

2. The mode, substantially as described, for making a shoe, it consisting in sewing the upper to the sole, and subsequently turning the upper and sole, as explained, and slitting the sole from its heel to, or nearly to, its shank, 70 between the stitching and the outer surface of the sole, and inserting in the slit and fixing to the inner surfaces thereof a crowning re-enforce, substantially as set forth.

ANDREW NICHOLS.
